UNITED STATES PATENT OFFICE

MARINO GENTILE, OF CHICAGO, ILLINOIS, ASSIGNOR OF ONE-HALF TO SAMUEL W. WEIS AND ONE-FOURTH TO GEORGE PICK, BOTH OF CHICAGO, ILLINOIS, AND ONE-TWENTIETH TO NATHAN SCHWARTZ, OF COOK COUNTY, ILLINOIS

CELLULOSE SHEET

No Drawing.

Application filed April 22, 1930. Serial No. 357,341.

Materials hitherto employed in the manufacture of wrapping sheets, cartons, films and other containers or wrappers for food and other products have, for the most part, heretofore consisted of ordinary pasteboard, cardboard, paper sheets of varying thicknesses more or less well adapted to exclude dirt, but incapable of preventing the passage of moisture or grease, or both, therethrough.

It is the object of the present invention to provide a cellulose material in various thicknesses which may range from tissue paper to thick cardboard, that shall be so treated as to render it both grease and moisture proof, whereby to greatly increase its usefulness as a wrapper or container for all kinds of food products, so as to preserve the latter from contamination by moisture or grease, and, in the case of articles containing moisture or grease or oil, to prevent the moisture, grease or oil from working through the wrapper or container.

In carrying out my present invention, I take a sheet of cellulose material, and to this sheet I apply a coating or covering of nitro-cellulose dissolved in a suitable solvent, such as ethyl-acetate, amyl acetate, ether, cellosolve (which latter is a trade name for a coal tar derivative), etc., which yields a thick or viscous product, which is thinned to a freely flowing state by the addition of a suitable amount of alcohol. To this nitro-cellulose solution is then added a nonhygroscopic material which renders the same soft and more or less pliable, when dry, and also causes it to adhere evenly and uniformly to the sheet base. Materials which satisfactorily serve to render the nitro-cellulose solution adhesive are castor oil and tricresolphosphate.

It is to be distinctly understood that the base may consist of a sheet of any cellulose material, such as cardboard, and papers of all kinds, such as semitranslucent papers, manila paper, parchment and semi-parchment sheets, whether made of linen, wood, rags, rope, bagasse, pappus grass or other cellulose materials.

The coating solution can be applied to the base in any suitable way, as by dipping the base sheet in, or drawing it through, a body

of the coating solution, or by flowing the latter over, or brushing it on, the base sheet. The coating penetrates the fibrous structure of the base, and when dry, the resultant product is a sheet that is non-porous and impervious to dust, grease and moisture, and thus excellently adapted to serve the purposes of a sanitary wrapper or container, especially for food products, medicines, and the like, and low in cost of materials and manufacture.

I claim:

As a new article of manufacture, a grease and moisture proof flexible material adapted to be used for wrapping sheets, cartons and the like, having a paper base coated with a characteristic film consisting essentially of transparent nitro-cellulose containing a modifying agent, from the group consisting of castor oil and tricresyl phosphate, that renders the film soft and pliable when dry and which causes the film to adhere evenly by penetration of the fibrous structure of the base.
